[57] CLAIM

The ornamental design for a dispensing carton for sheet material, substantially as shown and described.

DESCRIPTION

FIG. 1 is a perspective view of a dispensing carton for sheet material showing our new design;

FIG. 2 is an elevational view showing the end not seen in FIG. 1;

FIG. 3 is a top plan view, and

FIG. 4 is an elevational view thereof showing the side not seen in FIG. 1.

The dash marks in FIGS. 1 and 3 are indicative of the location of the openings in the carton.

FIG. 1

FIG. 2

FIG. 3

FIG. 4
